UNITED STATES PATENT OFFICE.

JUDD W. HULBERT, OF HARTFORD, OHIO.

METALLIC TIE.

No. 841,973.

Specification of Letters Patent.

Patented Jan. 22, 1907.

Application filed May 19, 1906. Serial No. 317,777.

To all whom it may concern:

Be it known that I, JUDD W. HULBERT, a citizen of the United States, residing at Hartford, in the county of Trumbull and State of Ohio, have invented certain new and useful Improvements in Metallic Ties, of which the following is a specification.

This invention relates to metallic railroad-ties.

One object of the invention is to provide a simple, inexpensive, durable, and efficient tie to supersede the usual wooden tie.

Another object of the invention resides in the provision of a railroad-tie embodying such characteristics as to obviate the use of spikes.

It is still further designed to provide a metallic railroad-tie of such construction as to insure a firm connection therebetween and the rails and also to permit of the ready removal therefrom of the rails, if desired.

With the above objects in view the present invention rests in the combination and arrangement of parts hereinafter more specifically referred to, illustrated in the accompanying drawings, and particularly pointed out in the appended claims.

In the drawings, Figure 1 is a plan view of my invention. Fig. 2 is a longitudinal sectional view. Fig. 3 is a transverse sectional view on the line *a a* of Fig. 1. Fig. 4 is a transverse sectional view on the line *b b* of Fig. 1. Fig. 5 is a perspective view of a modified form of my invention.

Referring now to the accompanying drawings, and more particularly to Figs. 1 to 4, inclusive, the reference character 1 indicates the body of the tie provided with a removable bottom 2, with its upper face provided at each end with a rail-engaging lip 3, each lip having its under face beveled to correspond with the bevel of the base-flange 4 of the rail 5. Formed through the body 1 of the tie, near each end thereof, is a longitudinal slot 6, in each of which is slidably mounted a standard 7. Each standard has a foot 8, designed to work in the oppositely-disposed grooves 9 at the bottom of each of the slots 6. It will thus be seen that the standards 7 have sliding movement in the slots 6, with the bottoms of their feet 8 sliding upon the upper faces of the removable bottom.

The standards 7 project slightly above the upper faces of the body 1, and intermediate the ends of the body there is formed a raised

portion 10, resulting in the recesses 11 in the upper face of the body between each of the lips 3 and said raised portion.

A clamping member 12 is designed to embrace the upper end of each of the standards 7 and slide upon the bottom of the corresponding recess 18 of the body 1. The opposite edges of each clamping member 12 are reduced to form oppositely-disposed seats 13, for a purpose presently explained, while the outer under face of each clamping member 12 is beveled, as at 14, to correspond with the bevel of the base-flange 4 of the rail 5. It will thus be understood that the clamping members 12 coöperate with the corresponding lip 3 of the body 1 to hold the rails 5 firmly against accidental displacement.

The clamping members 12 are secured to the upper ends of the standards 7 by means of suitable fastenings *a*. In order to insure a tight engagement of the clamping members 12 with the rails, I employ wedge-blocks 15. It will be seen that each wedging-block 15 has a beveled edge 16, whereby the clamping member 12 is engaged with the base-flange of the rail. Downward movement upon the blocks will cause sliding movement of the respective clamping members. Each wedging-block 15 has a recess 17 in one side adapted to aline with a notch 18 in the body 1 to permit the insertion thereinto of a tool (not shown) whereby the wedging-blocks may be lifted out of the body to permit sliding movement of the standards 7 and their corresponding clamping member 12 away from the corresponding rails to permit of removal of the latter. The wedging-blocks 15 project normally above the upper faces of the recesses 11, and in order to protect the interior parts of the tie from weather and consequent possible corrosion I provide a top plate 19. Aside from the fact that the top plate 19 protects the interior parts of the tie from the weather, it also serves to prevent movement of the standards 7 and the clamping members 12 away from the corresponding rails. This top is bifurcated at each end to form oppositely-disposed pairs of fingers 20, designed to overlap the clamping members 12 and rest upon the aforesaid seats 13 of each of the clamping members. This plate has a recess 21 formed in its under face at the base of each of the aforesaid bifurcations to fit over the corresponding wedge-block 15. Upon each side of each of

100

105

110

the recesses 21 is a foot 22, designed to rest in the aforesaid recess 11 upon corresponding sides of the slots 6, between the shoulder 22 of the raised portion 10 and the end of the corresponding clamping-block 12.

By reason of the peculiar connection of the top plate 19 with the body of the tie the plate cannot move longitudinally or laterally without first being lifted from the tie. However, 10 I prefer to more securely hold the plate upon the tie, and therefore I provide the plate 19 with a perforation 23, designed to aline with the perforation 24, formed through the raised portion 10 of the body 1 and the bottom 2, for the reception of bolt 25, having one of its ends screw-threaded for the engagement of the nut 26 therewith.

In Fig. 5 it will be seen that the body 27 is not hollow, but that it is provided with an intermediate raised portion 28, resulting in the oppositely-disposed shoulders 29, for a purpose presently understood. An integral lip 30 is formed at each end of the body 27 and provided with an undercut wall 31, designed to fit upon the base-flange 32 of the rail 33 for coöperation with the undercut wall 34 of each of the clamping members 35, which latter have their outer ends abutting against the corresponding shoulders 29 of the raised portion 28 of the body 27. These clamping members 25 are each held in place removably by means of the pairs of bolts 36, which have their upper ends screw-threaded for the reception of the nuts 37.

35 From the foregoing it will be seen that I herein describe two forms of my invention, and in either form the use of spikes is obviated. The elements of both forms are composed, preferably, of metal and are therefore 40 more substantial than the ordinary wooden ties, which latter frequently rot or otherwise deteriorate and cause disasters by reason of spreading of the rails. In my invention

there is a positive clamping action between the sides of the rails, whereby the opposite rails cannot possibly move toward or away from each other.

What is claimed is—

1. A metallic tie comprising a body having a rail-engaging lip at each end, spaced slots 50 arranged adjacent the corresponding lips, a standard arranged to slide in each slot, and clamping members disposed at the upper end of each standard for coöperation with the corresponding lip to prevent displacement of the rails with respect to each other, a wedging-block arranged in each slot for coöperation with the corresponding standard and clamping member and a top plate.

2. A metallic tie comprising a body having 60 a rail-engaging lip at each end and a raised portion intermediate its ends and also having a slot between each lip and said raised portion, each slot having oppositely-disposed grooves, a standard mounted in each slot and 65 provided with a foot for sliding engagement in said grooves, a clamping member carried at the upper end of each standard for coöperation with the corresponding lip to prevent displacement of the rails with respect to each 70 other, a wedging-block mounted in each of said slots to force the corresponding standard and clamping member toward the corresponding lip, a top plate upon the tie having its opposite ends bifurcated to fit upon 75 the clamping members, and a bolt passed through the body of the tie to prevent accidental displacement of the top plate.

In testimony whereof I have signed my name to this specification in the presence of 80 two subscribing witnesses.

JUDD W. HULBERT.
